AIR CONDITIONING APPARATUS

Louis D. Houlis, Cincinnati, Ohio

Application April 15, 1939, Serial No. 267,988

4 Claims. (Cl. 236—44)

This invention relates to new and useful improvements in air conditioning apparatus.

One object of the invention is to provide an improved apparatus for automatically regulating and controlling the temperature and humidity of circulating air and being particularly adapted for use in maintaining the proper temperature and humidity conditions within the interior of baker's "proof boxes," or other storage chambers.

An important object of the invention is to provide an improved conditioning unit, through which the air to be conditioned is circulated, said unit being provided with a dry bulb thermostat which is disposed in the path of the circulating air and which controls the temperature thereof; the humidity of the air being controlled by a wet bulb thermostat which is also located within the unit in the path of the circulating air.

Another object of the invention is to provide an improved air conditioning unit wherein the admittance of steam alone is depended upon to control the humidity of the air, whereby the necessity of utilizing heated water for this purpose is eliminated.

A particular object of the invention is to provide an improved apparatus, of the character described, having a humidity control of the wet bulb type for regulating and controlling the humidity of the circulating air, said control being so arranged that the wet bulb action is obtained without the necessity of immersing the same in water or enclosing the same in a wet cover or "sock," whereby the entire area of the control element is exposed to the circulating air and a more sensitive and positive control obtained.

Another object of the invention is to provide an improved air conditioning unit wherein steam is admixed with the circulating air to control the humidity thereof, together with means for utilizing the steam condensate or water for maintaining the bulb or element of the humidostat in a moistened condition, whereby the use of auxiliary water in the system is entirely eliminated.

A further object of the invention is to provide an improved air conditioning unit having an elongate casing through which the air is circulated, with means in the casing for heating the air and also humidifying the same as it passes through said casing; the heating means being controlled by a thermostat which is located at the inlet side of the casing in advance of the heating and humidifying means; the

humidity of the air being regulated and controlled by a humidostat which may be located either in advance of the heating and humidifying means or behind said means near the outlet side of the casing, the arrangement making for a simple and compact structure which efficiently and accurately controls the temperature and humidity of the circulating air.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a perspective view of a baker's proof box, having an air conditioning apparatus, constructed in accordance with the invention, mounted thereon for conditioning the air which is circulated through said box.

Figure 2 is a partial plan view of the air conditioning unit, constructed in accordance with the invention,

Figure 3 is a partial side elevation of said unit, having a portion of its wall broken away to more clearly show the interior thereof,

Figure 4 is a transverse, vertical, sectional view, taken on the line 4—4 of Figure 2,

Figure 5 is a plan view of a modified form of the invention and having portions of its top broken away to clearly illustrate the interior,

Figure 6 is a side elevation of the unit shown in Figure 5, with the portions of the side wall broken away,

Figure 7 is a transverse, vertical, sectional view, taken through one of the steam jets,

Figure 8 is a plan view of still another form of the invention, and

Figure 9 is a side elevation of this form of the invention.

In the drawings, the numeral 10 designates a housing which is substantially rectangular in cross-section. The housing may be formed in any suitable manner and is provided with insulated walls which have vertical air inlet ducts 11 secured thereto. The upper ends of the inlet ducts 11 are connected to a longitudinally extending manifold 12 which overlies the top of the housing. The manifold is connected with an air conditioning unit A, which will be hereinafter described and the conditioned air is circulated through the manifold and into the vertical ducts 11. From the ducts, the conditioned air passes through openings 13 and into the in-

terior of the housing. The air escapes from the interior of the housing through openings 14 provided in vertical outlet ducts 15 which are disposed on the wall opposite the ducts 11. The upper ends of the outlet ducts 15 are connected with a longitudinally extending manifold 16, which overlies the top of the housing and said manifold is connected to the air conditioning unit A. Manifestly, conditioned air is constantly circulated through the interior of the housing 10 and a continuous cycle of the air passing through the conditioning unit A is maintained.

The housing 10 may be utilized for various purposes but, as shown, is what is ordinarily known as a baker's proof box. The box is provided for receiving the bread dough after the same has been placed in the pans and prior to the baking of the bread. The dough is placed in the proof box and remains therein until it has risen and is otherwise ready for the baking operation. While the dough is within the box 10, it is necessary that the temperature and humidity of the air which is circulating through said box be maintained at the predetermined and desired point. The box is, of course, provided with suitable hinged doors 10', whereby access to the interior thereof may be readily had.

The invention primarily resides in the conditioning unit A which, as shown, is mounted on the top of the box or housing 10. It is noted that the box or housing 10 forms no part of the present invention and has been shown merely to illustrate one use of the conditioning unit A. The unit A could be employed for maintaining the proper temperature and humidity conditions within the fermentation room of a bakery or it could be employed for properly regulating and maintaining the condition of air which is circulated through any closed chamber or enclosure.

The conditioning unit A includes an elongate casing 20 which is substantially rectangular in cross-section, as is clearly shown in Figure 2. An inlet opening 21 is formed in one end wall of the casing 20 and this opening is surrounded by an outwardly directed flange 22, to which the manifold 16 may be connected, whereby air is introduced into the interior of the casing. A blower housing 23 is mounted within the casing and is secured to the end wall opposite that in which the inlet opening 21 is provided. The housing 23 has a suitable fan or blower 24 mounted therein and adjacent the fan the housing is formed with an opening 25. The shaft 26 of the fan projects through the end wall of the casing 20 and is coupled to a suitable electric motor or other drive means 27, which motor is supported on a bracket secured to the exterior of the casing. When the motor 27 is operated to rotate the blower or fan 24, air is drawn longitudinally through the casing, said air being pulled from the manifold 16 so as to flow toward the opening 25 in the blower housing 23.

The air which is drawn into the blower housing by the fan 24 is forced outwardly from said housing through an outlet opening 29, which is provided in the side wall of the casing 20. The opening 29 is surrounded by a flange 30 to which the manifold 12 is connected. With this arrangement, it will be manifest that the fan 24 serves to draw the air from the manifold 16, through the casing 20 and then outwardly through the manifold 12. From the manifold 12, the air passes downwardly through the vertical ducts 11, then transversely of the box or

housing 10 and into the vertical outlet ducts 15, from which said air passes to the manifold 16 to complete the cycle. So long as the blower or fan 24 operates, a constant circulation of air through the conditioning unit casing 20 and also through the interior of the box 10, is maintained.

For heating the air which is circulated through the casing 20, a radiator 31 is provided. This radiator is located nearer to the inlet opening 21 and includes the usual headers 32, which have the transversely extending steam pipes 33 disposed therebetween. The headers are secured to the side walls of the casing by suitable angle bars 34. Steam is supplied to one of the headers 32 by an inlet pipe 35 which extends through the side wall of the casing 20, as is clearly shown in Figures 2 and 3. A thermostatically operated valve 36 is connected in the line 35 and this valve, as will be hereinafter explained, is adapted to control the admittance of steam to the radiator 31.

A hand operated control valve 37 is also connected in the inlet pipe 35 and beyond said valve 25 the pipe is coupled to a T 38. The T has connection with an inlet line 39 which leads from a suitable source of steam supply. Manifestly, when the hand valve 37 is opened, the control of steam to the radiator 31 is accomplished by means of the thermostatically operated valve 36.

The valve 36 is controlled by a thermostat 40 which is connected to said valve by the usual flexible cable 41. The thermostat 40 is mounted in the top of the casing 20 immediately adjacent the inlet opening 21, whereby the bulb or element 42 of said thermostat depends downwardly into the interior of the casing and directly in the path of the air entering the interior thereof. The bulb or element has been shown in the form of a coil, but it is pointed out that any suitable thermostat, of the dry bulb type, and such as may be purchased on the open market, may be employed.

The thermostat 40 may be adjusted to maintain the temperature of the circulating air at a desired point. If the temperature falls below such a point, the thermostat acts to open the valve 36 and admit more steam to the steam pipes 33 of the radiator 31. Such action will cause a heating of the air circulating through the casing, with the result that the temperature of said air will be raised. When the temperature of the air reaches a predetermined point, the dry bulb thermostat 40 acts to close the valve 36 and shut down the steam supply to the radiator, whereby continued heating of the air is halted. In this manner, the thermostat provides a positive means of regulating and controlling the temperature of the circulating air. Since the element 42 of the thermostat is disposed directly in the path of the circulating air and has its entire outer surface exposed to said air, a very sensitive and accurate control of the temperature may be obtained.

For controlling the humidity of the air circulating through the casing, a vertically extending spray pipe 43 is provided. The spray pipe is disposed substantially at the center of the casing and extends contiguous to the steam radiator 31, as is clearly shown in Figure 2. The upper end of the pipe 43 is connected to a steam line 44 which extends laterally and transversely of the casing and projects through the side walls thereof. The line 44 has a thermostatically operated valve 45 connected therein and also has

a hand valve 46 beyond the thermostatic valve. Beyond the valve 46, the line 44 is extended and is coupled to the T 38 which has the steam line 39 connected therein. In this manner, the perforated spray pipe 43 is supplied with steam from the line 39, said steam passing through the pipe 44 and past the manually operated valve 46 and thermostatically operated valve 45. When the hand valve 46 is open, the flow of steam to the perforated spray pipe 43 is controlled entirely by the valve 45.

The valve 45 is controlled in its operation by a thermostat 47, which is of the wet bulb type. The thermostat is connected to the valve 45 by the usual cable 48 and said thermostat is mounted in the top of the casing adjacent the thermostat 40. The element 49 of the thermostat is in the form of a coil and extends substantially throughout the vertical length of the casing 20 and this coil is filled with a suitable gas or other fluid, which is responsive to, or affected by, temperature changes. Since the thermostat is located adjacent the thermostat 40, the element 49 of said thermostat is disposed directly in the path of the air entering the casing.

It is well-known that a thermostat of the wet bulb type must have its element maintained in a moist or wet condition in order to properly operate. For maintaining the element 49 in a moistened condition, a wick 50 is disposed within the coil of said element and has its upper end suitably fastened within the upper end thereof. The lower end of the wick extends from the lower end of the element and is located in the bottom of the casing 20. Some of the steam which is ejected into the interior of the casing from the steam spray pipe 43 will condense and precipitate to the bottom of the casing. This condensate will, of course, be water and will accumulate within the lower end of the casing, as shown in Figures 3 and 4. A predetermined level of this water is maintained in the bottom of the casing since the water outlet pipe 51 is spaced a predetermined distance from the bottom of said casing. Therefore, the wick 50 will depend downwardly into the water which is stored in the lower end of the casing 20 and capillary attraction will draw the water upwardly into the wick 50. The wick is thus maintained in a wet condition and this saturated wick will serve to maintain the element 49 of the thermostat 47 in a moistened condition, whereby its operation is assured.

With the above arrangement, it is not necessary to immerse the thermostat element 49 in water and neither is it necessary to enclose the same in a wet cover or sock. Thus, the entire outer surface of the element 49 is exposed at all times to the circulating air and this brings about a much more sensitive and accurate control. It will be evident that if the circulating air falls below a predetermined humidity, the thermostat 47 will operate the valve 45 to admit steam to the pipe 44 and the spray 43, whereby steam will be introduced into the air. The addition of this steam will immediately raise the humidity of said air and when said humidity reaches a predetermined point, as controlled by the adjustment of the thermostat 47, the valve 45 is closed to shut off the admission of steam. In this manner, a most sensitive and accurate control of the humidity of the air circulating through the casing is obtained.

Beyond the steam spray pipe 43 and within the interior of the casing 20, a suitable baffle

unit 52 is mounted. The unit 52 extends transversely of the casing and is secured to the side walls thereof by suitable angle bars 53. The unit includes a plurality of offset baffles 54 which extend vertically throughout the height of the casing. The baffles in one-half of the unit are offset in a direction opposite to the baffles in the other side of the unit, as is clearly shown in Figure 2. This arrangement provides for an unrestricted continuous passage 55 at the center of the baffle unit. The air which is passing through the casing must pass through the baffle unit and, as it strikes the offset baffles and passes therebetween, it is caused to take a circuitous path, whereby the excessive moisture or water in the air is knocked out. The air which flows through the central passage 55 is not subjected to any of the baffles but may pass directly to the blower or fan 24. For controlling the flow of air through the passage 55, a vertically extending, pivotally mounted damper 55a may be mounted centrally of the baffle unit and may be readily adjusted to control the flow of air through said passage.

In the operation of the device, the thermostat 40 is adjusted to a predetermined point, whereby the temperature of the air which is being circulated will be maintained at that point. Similarly, the wet bulb thermostat 47 is adjusted so that the humidity of the air circulating through the casing will also be maintained at a predetermined point. When the electric motor 27 is operated to operate the fan or blower 24, air is drawn into the casing 20 through the inlet opening 21. This incoming air strikes the element 42 of the thermostat 40 and causes said thermostat to act in the event that the temperature of said air is not at the proper point. If the temperature of the air is below that at which it is desired to maintain the same, the thermostat 40 operates the valve 36 to admit more steam to the radiator 31. Thus, the air flowing through the casing will pass through the steam pipes 33 of the radiator and its temperature will be raised.

The incoming air will also strike the element 49 of the wet bulb thermostat 47 and in the event that the humidity of this air is below that at which the thermostat is adjusted, then said thermostat will open the valve 45 to admit steam to the spray pipe 43, whereby steam will be admitted into the interior of the casing into contact with the air flowing therethrough. Steam will be admitted from the spray pipe 43 in accordance with the lack of proper humidity. Thus, it will be seen that the two controls 40 and 47 accurately control the temperature and humidity condition of the air.

After contacting the elements 42 and 49 of the thermostat and the wet bulb thermostat respectively, the air passes through the steam pipes 33 of the radiator 31, after which said air flows past the steam spray pipe 43. If steam is being admitted, this steam will be admixed with the air to raise the humidity thereof. After passing the steam pipe 43, the air flows through the baffle unit 52. As has been explained, the offset baffles cause the air to take a circuitous path therethrough, whereby excessive moisture or water is knocked out of the air. This moisture and water will be caught by the baffles and will flow downwardly along said baffles by gravity and to the lower end of the casing 20. After passing through the baffle unit, the air is drawn into the

fan or blower housing 23 and is then forced outwardly through the outlet 29 for re-circulation.

The device comprises a compact and unitary structure which will accurately control the temperature and humidity condition of the air circulated therethrough. The thermostat 47 is of the wet bulb type and the arrangement provides for maintaining the element 49 in a moistened or wet condition, without covering the exterior surface of said element, whereby increased sensitivity of control may be obtained. If desired, the upper end or top of the casing 20 may be provided with an access opening 56 which is normally closed by a suitable cover (not shown). Also the radiator 31 may be provided with the usual steam trap 57 which is connected by means of an elbow 58 to the lower end or bottom of the casing, whereby the condensate is conducted to said lower end. The device comprises a minimum number of parts and any desired spray head or means can be employed in place of the particular steam spray pipe 43 which is illustrated. The blower or fan 24 may be any of the well known types now on the open market and may be driven by any suitable means other than the motor 27.

It is not essential that the wet bulb thermostat 47 be located adjacent the inlet opening 21 of the casing and, in Figures 5 to 7, said thermostat is shown as located between the baffle unit 52 and the blower housing 23. In this form of the invention, the thermostat operates in the same manner to control the humidity of the air circulating through the interior of the casing. As is clearly shown in Figure 5, said thermostat is aligned with the central passage 55 which is formed in the baffle unit, whereby a direct and unrestricted flow of air may strike the thermostat element 49.

In this form of the invention, the wick 50 is eliminated and in place of said wick a vertically extending tube 60 is disposed within the coil of the element 49. The tube is bent upon itself at its lower end so as to extend parallel to the bottom of the casing 20 and this lateral portion 61 projects into the baffle unit 52. Upon entering the baffle, the tube is bent upwardly to provide a vertical portion 62 which has its upper end communicating with a funnel 63. The funnel is secured to one side of the baffle unit 52.

The funnel 63 is adapted to catch the steam condensate which flows downwardly through the pipe 62 and then upwardly through the tube 60. This condensate, which is water, overflows the upper end of the pipe and trickles downwardly within the element 49, whereby said element is maintained in a moistened or wet condition. It is noted that, if desired, this method of maintaining the element 49 in a moistened condition could be utilized when the thermostat is located in the position shown in Figures 2 to 4.

As has been pointed out, the spray pipe 43, illustrated in the first form, may be eliminated and other means for admitting steam provided. In Figures 5 and 6, another form of steam inlet is shown. In this instance, an angular steam inlet pipe 44' is connected with the T 38 which has the steam supply line 39 connected therewith. The pipe 44' has the manually operated valve 46 and the thermostatically operated valve 45 connected therein. The inner end of the pipe 44' is connected with a laterally extending pipe 64 which is located near the bottom of the casing 20. The pipe 64 has a plurality of steam jets 65 connected therein. Each jet includes a

body 66, as shown in Figure 7, which is provided with an outlet nozzle 67 in its upper end. The steam which is admitted to the pipe 64 is ejected upwardly from the nozzle 67, as is clearly shown by the arrows in Figure 6. The body 66 is formed with diametrically opposed lugs 68 in which are supported a pair of eduction tubes 69. The lower end of each tube 69 extends into the water in the bottom of the casing 20, while the upper end of said tube is bent inwardly so as to extend contiguous to the nozzle 67.

When the valve 45 is operated to admit steam to the pipe 64, the steam is ejected upwardly from the nozzle 67. The ejection or emission of the steam from the nozzle 67 creates a suction in the tubes 69, whereby water is drawn upwardly through the tubes 69 and admixed with the steam. This water is sprayed upwardly in the path of the air which is moving through the casing 20 and a portion of this water is caught by the funnel 63. This water, as has been explained, flows downwardly from the funnel 63 through the pipe 62 and then upwardly in the tube 60. The provision of the eduction tubes 69 assures that sufficient water will fall downwardly through the funnel to maintain the element 49 in a moistened or wet condition. Of course, the water which is sprayed upwardly into the path of the circulating air will serve to wash the air as the same passes therethrough. As in the first form, the steam is depended upon to raise the humidity of the air when the same falls below a predetermined point.

In Figures 8 and 9, still another form of the invention is shown. In this form, a wet bulb thermostat 47', similar in construction to the wet bulb thermostat 47, is located between the baffle unit 52 and the blower housing 23. The thermostat 47' is formed with a solid rod or element 49' instead of with a coiled element, as is the thermostat 47. As is clearly shown in Figure 8, the thermostat is located in alignment with the passage 55 in the baffle unit 52.

The interior construction of this form is substantially the same as that shown in Figures 2 to 4, with the exception that a water spray pipe 70 is disposed between the steam pipe 43 and the baffle unit 52. As is clearly shown in Figure 8, the pipe 70 extends transversely of the casing 50 and is supported in suitable brackets 71 which are located at substantially mid-height of said casing. The pipe is provided with a plurality of spray heads 72 which are directed so as to eject water into the path of the circulating air. The pipe 70 is connected with a water inlet line 73 which may lead from a suitable source of water supply. The water may be ejected continuously from the spray heads 72 and it will be obvious that as the air passes through said spray, said air is washed. The excessive water which may be introduced into the air by the spray is knocked out by the baffles 54. However, the air which passes through the unrestricted passage 55, which is controlled by the damper 55a, is laden with water and this stream of air will contact the rod or element 49' of the thermostat. This moisture-laden stream of air is sufficient to maintain the element 49' in a moistened or wet condition, whereby the operation of the thermostat 47' is assured. With this arrangement, the moisture-laden air is utilized to maintain the thermostat element 49' moistened and the necessity of immersing said element in water or enclosing the same with a wet cover or sock, is eliminated. The operation of this form of the

invention is substantially the same as the other forms, hereinbefore described.

It is pointed out that in all forms the dry bulb thermostat 40 maintains and regulates the temperature of the air which is circulating through the casing 20, while the wet bulb thermostat 47 is utilized to control the humidity. In all forms, the element of the thermostat is supplied with moisture while its exterior surface is completely exposed to the air flowing through the casing, whereby wet coverings or "socks" enclosing said element are eliminated, and this provides for a very sensitive and accurate control. The steam alone is utilized to add humidity to the circulating air and this eliminates the necessity of providing heated water to control humidity. In the form shown in Figures 8 and 9, the water spray is primarily for the purpose of washing the air and also for permitting a stream of moisture-laden air to strike the element 49' of the thermostat 47'. It is obvious that the location of the thermostat is not important but so long as it is in the path of the circulating air, it will accurately control the humidity thereof.

The foregoing description of the invention is explanatory thereof and various changes in the size, shape and materials, as well as in the details of the illustrated construction, may be made, within the scope of the appended claims, without departing from the spirit of the invention.

What I claim and desire to secure by Letters Patent is:

1. An air conditioning apparatus including, an elongate casing having an inlet at one end and outlet at its opposite end, means for circulating air longitudinally through the casing, a heater extending transversely of the casing for heating the air passing therethrough, a thermostat having a dry bulb disposed between the heater and inlet directly in the path of the incoming air for controlling the operation of the heater to maintain the circulating air at a desired temperature, a steam spray means within the casing beyond the heater for introducing steam into the air circulating through the casing to control the humidity thereof, a thermostat having a wet bulb element mounted in the casing beyond the spray means for controlling the admission of steam in accordance with the humidity of the circulating air, and means for directing an uninterrupted stream of moisture-laden air onto the element of the wet bulb thermostat to maintain the same in a moistened condition without covering the exterior surface thereof.

2. An air conditioning apparatus including, an elongate casing having an inlet at one end and an outlet at its opposite end, means for circulating air longitudinally through the casing, a heater extending transversely of the casing for heating the air passing therethrough, a thermostat having a dry bulb disposed between the heater and inlet directly in the path of the incoming air for controlling the operation of the heater to maintain the circulating air at a desired temperature, a steam spray means within the casing beyond the heater for introducing steam into the air circulating through the casing to control the humidity thereof, a thermo-

stat having a wet bulb element mounted in the casing beyond the spray means for controlling the admission of steam in accordance with the humidity of the circulating air, and a baffle unit 5 between the steam spray means and the wet bulb thermostat for separating excessive water from the circulating air, said baffle having an unrestricted passage aligned with the element of the wet bulb thermostat, whereby a constant stream of moisture-laden air is directed onto said element to maintain the same in a moistened condition.

3. An air conditioning apparatus including, an elongate casing having an inlet at one end and an outlet at its opposite end, means for circulating air longitudinally through the casing, a heater extending transversely of the casing for heating the air passing therethrough, a thermostat having a dry bulb disposed between the heater and inlet directly in the path of the incoming air for controlling the operation of the heater to maintain the circulating air at a desired temperature, a steam spray means within the casing beyond the heater for introducing steam into the air circulating through the casing to control the humidity thereof, a thermostat having a wet bulb element mounted in the casing beyond the spray means for controlling the admission of steam in accordance with the humidity of the circulating air, a water spray 20 between the steam spray and wet bulb thermostat for introducing water into the casing, and a baffle unit between the water spray and the wet bulb thermostat for separating excessive water from the circulating air, said baffle having an unrestricted passage aligned with the element of the wet bulb thermostat, whereby a constant stream of moisture-laden air is directed onto said element to maintain the same in a moistened condition.

4. An air conditioning apparatus including, an elongate casing having an inlet at one end and an outlet at its opposite end, means for circulating air longitudinally through the casing, a heater extending transversely of the casing for heating the air passing therethrough, a thermostat having a dry bulb disposed between the heater and inlet directly in the path of the incoming air for controlling the operation of the heater to maintain the circulating air at a desired temperature, a steam spray means within the casing beyond the heater for introducing steam into the air circulating through the casing to control the humidity thereof, a thermostat having a wet bulb element mounted in the casing beyond the spray means for controlling the admission of steam in accordance with the humidity of the circulating air, a baffle unit between the steam spray means and the wet bulb thermostat for separating excessive water from the circulating air, said baffle having an unrestricted passage aligned with the element of the wet bulb thermostat, whereby a constant stream of moisture-laden air is directed onto said element to maintain the same in a moistened condition, and an adjustable damper in said passage for controlling the air flowing therethrough.

LOUIS D. HOULIS.
